UNITED STATES PATENT OFFICE

WILLIAM D. THOMPSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE

CAR ROOF

Application filed November 23, 1925. Serial No. 70,920.

This invention relates to car roofs and more particularly to that type of roof in which metal roof sheets are employed.

The invention relates more particularly to the connection between the sub-structure of the car and the roof sheets at the eaves, and has as a particular object to simplify, render more efficient and improve generally constructions of this character. Other objects, advantages and novel details of construction will appear more fully as this description proceeds, especially when considered in connection with the accompanying drawings, wherein

Fig. 1 is a fragmentary, transverse sectional view of a portion of a car roof constructed in accordance with my invention,

Fig. 2 is a fragmentary view of the roof structure illustrated in Fig. 1 at the eave thereof,

Fig. 3 is a side elevation of the structure illustrated in Fig. 2,

Fig. 4 is an enlarged vertical sectional view taken substantially on the plane indicated by line 4—4 in Fig. 3, and

Fig. 5 is an enlarged sectional view taken substantially on the plane indicated by line 5—5 in Fig. 4.

Referring now particularly to the drawings wherein like reference characters indicate like parts, it will be noted that there is illustrated a side plate 10 of the car to which the facia boards 11 are connected by means of bolts 12, while the side sheathing is indicated by the reference character 13. The sub-structure comprises mullions 14, purlins 15 and a ridge pole 16, upon which are arranged metal roof sheets 17 provided with upstanding edge flanges 18, the longitudinal joints between the roof sheets being weather-proofed by transverse caps 19 running parallel with the mullions 14.

Each transverse cap 19 is held against upward displacement by means of a shoulder bolt 20 riveted as at 21 to the transverse cap 19 and extending through an enlarged opening 22 in the associated mullion 14. The lower end of each bolt passes through an aperture 23 formed in the substantially horizontal arm of a knee brace 24 secured to the

side plate 10 for instance, by means of the bolts 12 and additional fastening bolts 25. The lower end of each shoulder bolt 20 is threaded to receive a nut 26, it being preferable to also associate with each bolt a lock washer 27.

The eaves end of each roof sheet is formed with a depending returnbent flange 28 extending under the roof sheet and terminating in an outwardly extending portion 29 forming an outwardly opening pocket 30. This outwardly opening returnbent roof sheet flange is positioned below the plane of the roof sheet and is arranged in a space or chamber 31, at the eaves of the car, formed by arranging the facia boards 11 a distance below the upper edge of the side plate 10 and extending the roof sheets out beyond the side plates to a point in substantially vertical alignment with the outer side of the facia boards.

Secured within the chamber 31 is an inner flashing strip 32 provided with a horizontal portion 33 extending under the returnbent flange 28 of the roof sheets and provided with a plurality of spaced upwardly projecting embossed portions 34 constituting bearing surfaces for the returnbent flange 28 and spacing this flange from the general plane of the portion 33 of this inner flashing 32. Associated in cooperative relation therewith is an outer flashing 35 having a returnbent portion 36 extending within the pocket 30 formed by the returnbent flange 28 of the roof sheets. This outer flashing 35 is arranged in superposed relation within the flashing 32 and also engages the roof sheet on the surface thereof diametrically opposed to the surface engaged by the embossed portions 34 of the inner flashing strip. The vertical portion 37 of flashing strip 35 is provided with a plurality of spaced inwardly extending embossed portions 38 arranged alternately in different horizontal planes and perforated to receive fastening members 39 which are passed therethrough and through the facia boards 11 into side plate 10. The embossed portions 38 with their openings are arranged in alternately different horizontal planes so that the passage of the fastening

means 39 through the facia boards 11 will not split or otherwise weaken the same. The inner flashing strips 32 are secured in place by means of fastening members 40 passing 5 through openings in the vertical portion 41 of this flashing strip.

While the embossed portions 34 of the inner flashing strip 32 provide bearing surfaces for the returnbent flanges of the roof 10 sheets, and while the embossed portions 38 are apertured to receive the fastening members 39 these embossed portions also afford spacing means for the flashing strips 32 and 35 so as to permit the escape of any moisture 15 which enters the chamber 31.

The herein described construction permits of a freedom of movement of the roof sheets 17 while preventing the same from moving outwardly and consequently down from off 20 the ridge of the car. The length of the bearing surfaces formed by the cooperating inner and outer flashing strips is such as to firmly hold the roof sheets at the eaves irrespective 25 of the upward movement of the roof sheets and consequently the inward movement of the returnbent flanges 28. Furthermore, the flashing strips are freely movable in an outward direction, in consequence of a bowing 30 of the side plates without altering the effect of their engagement with the returnbent flange of the roof sheets.

While the invention has been described and illustrated herein somewhat in detail, it will be readily apparent that various changes may 35 be resorted to without departing from the spirit and scope of this invention and to this end reservation is made to make such changes as may come within the purview of the accompanying claims.

40 What I claim as my invention is:

1. In a car roof the combination with a sub-structure, of a roofing sheet having a depending returnbent flange at an eave of the roof in spaced relation to the underside 45 of the roofing sheet, and inner and outer flashing strips co-operating to form a bearing for said flange of sufficient depth to form a non-shearing stop to limit the outward movement of said roofing sheet, said flashing strips being free to move outwardly relative to said roofing sheet.

2. In a car roof the combination with a sub-structure, of a roofing sheet having a depending returnbent flange at an eave of the roof, and inner and outer flashing strips co- 55 operating to form a bearing for said flange of sufficient depth to form a non-shearing stop to limit the outward movement of said roofing sheet, said flashing strips being free 60 to move outwardly relative to said roofing sheet, and spacing bosses formed on said flashing strips to provide a drainage space.

3. In a car roof, the combination with a sub-structure, of a roofing sheet having a de- 65 pending return-bent flange at an eave of the

70 roof in spaced relation to the underside of the roofing sheet whereby it may move inwardly and superposed flashing strips engaging said flange on opposed sides thereof and permitting relative outward movement between said strips and flange.

4. In a car roof, the combination with a sub-structure of a roofing sheet having a de- 75 pending return-bent flange at an eave of the roof, and superposed flashing strips engaging said flange on opposed sides thereof, one of said flashing strips being formed with an embossed portion spacing said flashing strips.

5. In a car roof, the combination with a sub-structure, of a roofing sheet having a de- 80 pending return-bent flange at an eave of the roof, an inner flashing strip forming a bearing for the flange of the roof sheet, and an outer flashing strip having a return-bent portion slidably engaging the return-bend of 85 said roofing sheet and adapted for movement outwardly relative to the said return bend of the roofing sheet.

6. In a car roof, the combination with a sub-structure, of a roofing sheet having a de- 90 pending return-bent flange at an eave of the roof, an inner flashing strip provided with embossed portions forming a bearing for the flange of the roof sheet, and an outer flashing strip spaced from said inner flashing strip by 95 embossed portions and having a return bent portion engaging the return-bend of said roofing sheet and holding the same in engagement with said embossed portions.

7. In a car roof, the combination with a sub-structure, of a roofing sheet having a de- 100 pending return-bent flange at an eave of the roof, an inner flashing strip provided with embossed portions forming a bearing for the flange of the roof sheet and spacing said flange therefrom, and an outer flashing strip having a return-bent portion engaging the return-bend of said roofing sheet and having embossed portions to space the same from 105 said sub-structure, the said embossed portions of the inner and outer flashing strips co-operating to form a drainage space.

8. In a car roof the combination of a sub-structure, a roofing sheet having a depending return-bent flange at an eave of the roof, and inner and outer flashing strips engaging 110 said roofing sheet flange, said outer flashing having a return-bent portion extending into the return-bent portion of said roof sheet flange and permitting a relative sliding movement laterally between said outer flashing and said roof sheet flange.

9. In a car roof the combination with a sub-structure, of a roofing sheet having a de- 115 pending return-bent flange at an eave of the roof, an inner flashing strip engaging said flange, and an outer flashing strip formed with a return-bent portion extending into the return-bend of said roofing sheet and slidably 120 laterally with respect thereto.

10. In a car roof, the combination with a
sub-structure, of a roofing sheet having a
return-bent flange at the eave of the roof
spaced inwardly from the edge of the roof
5 in spaced relation to the underside of the roof-
ing sheet, inner and outer flashing strips co-
operating to form a bearing for the said re-
turn-bent flange, the said flashing strips be-
ing provided with oppositely facing embossed
10 portions to provide means for spacing the
flashing strips from each other and for sup-
porting the said flange, and a return-bent por-
tion formed on one of the flashing strips to
form a non-shearing stop to limit the outward
15 movement of the roofing sheet while permit-
ting inward movement of the roofing sheet
and outward movement of the flashing strip.

11. In a car roof, the combination with a
sub-structure, of a roofing sheet having a de-
20 pending return-bent flange at the eave of the
roof, said flange being bent inwardly then
downwardly and then outwardly below the
said roof, an inner flashing strip having em-
bossed portions forming a bearing for the
25 outwardly extending portion of said return-
bent flange, and an outer flashing strip hav-
ing a portion bent inwardly then upwardly and
then outwardly to engage the said inwardly
downwardly and outwardly extending por-
30 tions of the said flange of the roofing sheet re-
spectively to limit outward movement of the
said roofing sheet, the said outer flashing
strip being adapted for movement outwardly
relative to the said return-bent flange of the
35 roofing sheet.

12. In a car roof the combination with a
sub-structure, of a roofing sheet having a de-
pending return bent flange at an eave of the
40 roof, and flashing strips engaging said flange
on opposed sides thereof, said flashing strips
cooperating to form a non-shearing stop to
limit the outward movement of said roofing
sheet while being movable outwardly rela-
tive to said flange.

45 In testimony whereof I affix my signature.
WILLIAM D. THOMPSON.
